(57) CLAIM

The ornamental design for a hat, as shown and described.

DESCRIPTION

1. Hat

1.1 is a perspective view of a hat showing my new design;

1.2 is a front view thereof;

1.3 is a back view thereof;

1.4 is a left side view thereof;

1.5 is a right side view thereof;

1.6 is a top view thereof;

1.7 is a bottom view thereof;

1.8 is a perspective view thereof; and

1.9 is a perspective in use view thereof.

The broken lines in the figures are for the purpose of illustrating portions of a hat and form no part of the claim.
